UNITED STATES PATENT OFFICE.

RUSSELL B. BENNETT, OF WESTERVILLE, OHIO.

COMPOSITION FENCE-POST.

1,079,829.

Specification of Letters Patent.

Patented Nov. 25, 1913.

Application filed August 13, 1912. Serial No. 714,920.

To all whom it may concern:

Be it known that I, RUSSELL B. BENNETT, citizen of the United States, residing at Westerville, in the county of Franklin and 5 State of Ohio, have invented certain new and useful Improvements in Composition Fence-Posts, of which the following is a specification.

This invention relates to the manufacture 10 of composition posts, more particularly of the type shown in Letters Patent No. 829,940, granted to me September 4, 1906.

The objects of the present invention are to produce a post of pronounced durability 15 and strength with minimum quantity of material, to provide a reinforcement which will not be displaced during the molding of the post and in which the longitudinal elements will be held in fixed relation; and 20 to provide a reinforcement of truss-like form which will not interfere with the insertion of the staple-receiving composition.

The invention consists in certain novel 25 features, all of which will be hereinafter first fully described and then more particularly pointed out in the claim following the description.

The invention is illustrated in the accompanying drawings, in which:

30 Figure 1 is a perspective view of a reinforcement for composition posts showing the parts of the same assembled before the post is formed around the same; Fig. 2 is a transverse vertical section of a mold showing a post formed therein; Fig. 3 is a detail plan view of a different form of brace or spacer for use in the reinforcement; Fig. 4 is a transverse section of a mold showing a post formed therein and provided with a 35 further form of reinforcement; Fig. 5 is a detail perspective view of the reinforcement shown in Fig. 4; Figs. 6, 7, and 8 are detail plan views of different forms of spacers.

In carrying out my invention, I employ a 45 plurality of longitudinal rods or braces 1 which may be of any desired number according to the outline desired for the finished post. I prefer to make the posts substantially triangular in horizontal section, 50 as I have found that this form avoids unnecessary weight and bulk, while possessing sufficient strength to resist severe strains. The longitudinal bars or rods 1 are passed through open wing ties or spacers 2 which 55 are arranged at intervals along the reinforcing rods and are substantially V-shaped,

as clearly shown, the reinforcing rods passing through openings provided therefor at the angle and at the ends of the spacers. In Figs. 1 and 2, the spacers are shown as 60 provided near their ends and in their outer edges with notches 3 whereby shoulders 4 are formed, and on their inner edges at their ends they are provided with the enlargements 5 whereby sufficient metal is 65 formed around the rod-receiving opening to support the rod and prevent the detachment of the spacer therefrom.

The reinforcement, consisting of the rods or bars and the ties or spacers fitted thereon, is placed within a mold 6 which is approximately triangular in cross section, and the concrete or other cementitious composition 7 is poured in to the mold so as to entirely fill the same around the several elements of the reinforcement. It will be readily noted upon reference to Fig. 2 that the shoulders or corners 4 of the reinforcement engage the lower downwardly converging walls of the mold so as to support 70 the reinforcement in proper spaced relation to the mold and permit the plastic composition to entirely fill the space between the reinforcement and the side of the mold so that the metallic members of the reinforcement 75 will be entirely inclosed by and embedded in the composition of the post. The mold will, of course, be of a length corresponding to the height desired for the post, and the longitudinal reinforcing bars will 80 be located at the corners of the post and will 85 extend the full length of the same.

The spacers or ties, by which the longitudinal reinforcing rods or bars are held in their proper spaced relation within the 90 mold while the post is being poured, may be of various forms and I have shown several which prove efficient. In Fig. 3, the spacer is substantially of the same form as that shown in Fig. 2, except that on its outer edges, near its angle, it is provided with outstanding spurs or teeth 8 and in its inner edge, adjacent its lower end or its angle, notches 9 are provided. In the form shown in Fig. 6, two spurs or teeth 10 are formed 95 on the outer edges of the spacer and two notches or recesses 11 are formed in each inner edge thereof. In Fig. 7, is shown a form of spacer in which the recess 3, indicated in the previously described forms, 100 is omitted, and the shoulder 12 springs directly from the straight outer edge of the 105

spacer. In this form, also, the enlargement 13 is reduced toward the end of the spacer and is disposed at an obtuse angle thereto in its lower portion, instead of being semi-circular, and the opening 14, to receive the bracing rod, is somewhat lower in the spacer. In Fig. 8, the spacer is shown without the enlargement on the inner edge thereof, the straight edge 15 of the end of the spacer 10 being reduced and the inner edge 16 thereof being straight.

The several forms of spacers just described are easily stamped out of sheet metal, and, with the exception of the form 15 shown in Fig. 7, a large number of the spacers may be stamped from a single strip of metal without any waste, while in the form shown in Fig. 7 may be produced with only so much waste as will be included between the lines of the inner edges of the main portion of the spacer and the highest point of the enlargements 13. It is not necessary, however, to employ sheet metal spacers, as stout wire may be utilized, and 20 in Figs. 4 and 5, I have shown the spacer as formed of stout wire 17 wrapped around the reinforcing bars 18 and so disposed as to present spaced eyes or loops 19 adapted to encircle the bars 18 whereby the said bars 25 will be maintained in their proper spaced relation. The free ends of the wire are bent slightly downward, as shown at 20, so as to rest upon the walls of the mold whereby the reinforcement will be supported out of 30 contact with the bottom of the mold and the composition for the post may be poured into the mold so as to flow entirely around the members of the reinforcement.

It will be readily noted from the foregoing description, taken in connection with the accompanying drawings, that I have provided a construction in which it will be impossible to displace the members of the reinforcement during the molding of the 40 post and that the post may be rapidly and cheaply produced, and when produced, will be effectually reinforced at the points where the strain is usually applied thereto. The longitudinal reinforcing bars, which will be 45

upright when the post is in position for use, 50 will be disposed at the corners of the post and the post will contain throughout its height a truss-like structure so that the maximum strength will be attained with a few reinforcing members. When the post 55 is in use, any strain placed thereon will be transmitted through the entire reinforcement, as the distance between the ties or spacers is short, and it will, consequently, be practically impossible to break the post. 60 The spacer cannot buckle, as it is held firmly within the concrete, and any strain which would tend to force apart the rods passing through the ends of the spacers must first crush the concrete below the point where the 65 strain is applied, and this strain will be resisted by the tensile strength of the spacer at its angle.

As the ties or spacers are V-shaped or have open tops, they offer no obstruction to 70 the pouring of the cementitious material into the mold nor do they interfere in any degree with the proper location of the staple-receiving composition strip, indicated at 21.

75 What I claim is:

A fence post comprising a substantially triangular body, a plurality of V-shaped spacers embedded therein and having their sides substantially parallel with the faces of 80 the body, each spacer having an eye at its apex and at each terminal and provided with a supporting projection on each outer side near each terminal, said projections constituting suspending points disposed between the terminals and the apex of the spacer, rods inserted through and inclosed and supported by the eyes in the spacers, and a penetrable composition in one face of 85 the body between the terminals of the 90 spacers.

In testimony whereof I affix my signature in presence of two witnesses.

RUSSELL B. BENNETT. [L.S.]
